(57) **CLAIM**

The ornamental design of a kitchen lid organizer, as shown and described.

DESCRIPTION

FIG. 1 is a perspective view of the kitchen lid organizer of this invention. As shown in FIG. 1, the kitchen lid organizer includes a number of V-notched vertical, substantially planar elements. The lids, shown with dotted lines, do not form any part of the claimed design; and,

FIG. 2 is a side elevational view of the kitchen lid organizer of this invention. The lids, shown with dotted lines, do not form any part of the claimed design.
